United States Patent Office

Des. 191,166
Patented Aug. 22, 1961

191,166

SINKER

Carl E. Abramson, 182 N. 17th St., San Jose, Calif.

Filed Aug. 28, 1959, Ser. No. 57,361

Term of patent 14 years

(Cl. D31—4)

Fig. 1.

Fig. 2.

Fig. 3.

Fig. 4.

Fig. 5.

FIG. 1 is a front perspective view, showing the top of a sinker embodying my new design;

FIG. 2 is a rear perspective view thereof;

FIG. 3 is a rear elevational view thereof on an enlarged scale;

FIG. 4 is a front elevational view thereof on an enlarged scale;

FIG. 5 is a bottom view thereof on an enlarged scale.

I claim:

The ornamental design for a sinker, as shown.
